UNITED STATES PATENT OFFICE

160,982

VEGETABLE SLICER

Elton F. Whitfill and Henry J. Talge, Kansas City,
Mo., assignors to John C. Heckery, Kansas City,
Mo., as trustee

Application November 9, 1949, Serial No. 5,948

Term of patent 14 years

(Cl. D89—1)

To all whom it may concern:

Be it known that we, Elton F. Whitfill and Henry J. Talge, citizens of the United States, residing in Kansas City, in the county of Jackson and State of Missouri, have invented a new, original, and ornamental Design for a Vegetable Slicer, of which the following is a specification, reference being had to the accompanying drawing, forming part thereof, in which

Fig. 1 is a front perspective view of a vegetable slicer embodying our new design,

Fig. 2 is a rear perspective view of same.
We claim:

The ornamental design for a vegetable slicer, substantially as shown.

ELTON F. WHITFILL.
HENRY J. TALGE.
